UNITED STATES PATENT OFFICE

2,107,688

TUNNEL MUCKING APPARATUS

Cecil M. Browner, Beaumont, Calif.

Application August 8, 1936, Serial No. 95,022

8 Claims.

(Cl. 214—90)

My invention relates generally to tunnel mucking apparatus, and particularly to apparatus of this character embodying improvements over the tunnel mucking machine forming the subject matter of my co-pending application Serial No. 36,908, filed August 19, 1935, now Patent No. 2,072,495 dated Nov. 2, 1937, and entitled Tunnel mucking machine, of which the present application is a continuation in part.

Among the improvements embodied in the invention which constitutes the subject matter of the present application are re-arrangements of the digging boom operating mechanism as well as the main boom and digging boom supporting means, whereby more efficient operation of the apparatus is secured. The improvements also include re-distribution and re-arrangement of the engine and its operating connections to the main boom and the digging boom, and the operative connection of the engine with a re-arranged conveyor for discharging the muck from the apparatus.

An important feature of the present invention is the improved arrangement of the front end of the apparatus whereby the main boom and the digging boom are operatively supported in a manner to permit easy and accurate swinging from side to side of these elements when required to dig a tunnel the full width of the apparatus, with the initial position of the apparatus and directional movement thereof unchanged except for predetermined forward motion.

Other important objects of my invention will be apparent from a reading of the following description taken in connection with the drawings, wherein for purposes of illustration I have shown a preferred embodiment of my invention.

Figure 1 is a general side elevational view of the embodiment showing the digging boom in an intermediate position.

Figure 2 is a view similar to Figure 1 but showing the digging boom in the position which it first assumes after a digging operation.

Figure 3 is a top plan view of the embodiment.

Figure 4 is a vertical longitudinal sectional view taken through Figure 1.

Figure 5 is a horizontal sectional view taken through Figure 4 approximately on the line 5—5 and looking downwardly in the direction of the arrows.

Figure 6 is a transverse vertical sectional view taken through the conveyor belt structure.

Figure 7 is a perspective view of the inner section of the digging boom.

Figure 8 is a longitudinal vertical sectional

view showing the arrangement of one of the digging boom operating racks.

Figure 9 is a horizontal sectional view taken through the front part of the front or outer section of the digging boom.

Figure 10 is a horizontal sectional view taken through the lower part of the boom support.

Figure 11 is an enlarged transverse vertical sectional view taken through Figure 10 approximately on the line 11—11.

Referring in detail to the drawings, the numeral 5 generally designates the frame of the tunnel mucking apparatus which comprises a chassis or base 6 which has a main elevated portion 7, a depressed portion 8 and a still further depressed front portion 9. Removably mounted by means generally designated 10 and 11 are trucks 12 and 13, respectively, for mounting the chassis on rails 14. It is to be understood that trucks 12 and 13 may be replaced by other rail-way trucks having a greater number of wheels, or may be replaced by caterpillar trucks to mount the device operatively on a surface devoid of rails. Under the front portion 9 of the chassis is a transversely arranged roller 15 which is arranged to engage the tops of the rails 14 or other supporting surface to prevent downward tipping of the front end of the chassis under the strain of the operation of the booms and the weight of the material dug.

Rising from the elevated portion 7 and from the rear extremity of the chassis 5 is the vertical standard 16 which is transversely arranged and from the left elevated portion 8 of the chassis rises a pair of transversely spaced standards 17 and extending from the tops of these standards 17 to the upper part of the standard 16 are the longitudinal braces 18. Extending rearwardly and upwardly from an intermediate portion of the standards 17 are longitudinal braces 19 which have their rear ends connected to short vertical standards 20 whose upper ends are connected by the cross member 21. Across the tops of the front ends of the brace members 19 is arranged and fixed the lower brace plate 22 whose front end is triangular in form and has in its apex the pivot 23. A similar brace plate 24 is mounted on the tops of the forward ends of the tubular frame members 18 and fastened thereto and to the upper ends of the standards 17. The front end of this plate is triangular in form and in the apex thereof is the upper pivot 25 which is axially aligned with the pivot 23. On the rear end of the upper brace plate 24 is the

pulley 26 over which the digging boom operating cable is trained.

The conveyor which is generally designated 27 comprises the two side walls 28 and 29 which are connected adjacent their lower ends by the supporting metal web 30 on which the top flight 31 of the conveyor belt which is generally designated 32 is slidably supported. The lower flight 33 of the conveyor belt works under the web 30 and rests on supporting rollers 34 which are mounted as clearly indicated in Figure 1 under the lower flight of the belt, whereby the lower flight of the conveyor belt is prevented from drooping below the lower edges of the side members 28 and 29 of the conveyor frame.

The conveyor frame has a generally horizontal portion 35 extending beyond the rear of the chassis 5 and the descending portion 36 which runs practically the length of the chassis 5 at the same angle to reach the hopper 37 the nature of which is clearly shown in Figure 4 and which is arranged on the top of the front extremity 9 of the chassis.

The rear end of the conveyor belt 32 runs over a roller on a shaft 38 which is mounted by belt tightening means generally designated 39 on the conveyor frame portion 35 and its opposite end is trained over the roller 39 which is mounted in brackets 40 on the lower part of the hopper 37 and within the front chassis portion 9 as illustrated in Figure 4. A suitable web 40 is irregularly formed to permit the conveyor frame to pass the front end of the chassis portion 7 at a lower level than the top of this chassis portion and similar irregular formations 42 are made in the relatively elevated portion 8 of the chassis to pass the conveyor frame.

The top 43 of the front extremity 9 of the chassis frame is semi-circular in form and level and on this run the rollers 44 which are mounted on shafts 45 in the arcuate foot 46 which forms the lower end of the boom support which is generally designated 47, the rollers 44 being arranged in openings 48 in the foot 46 as clearly shown in Figures 10 and 11 of the drawings. Inwardly and upwardly inclined side members 49 of L-shaped cross-section or other suitable cross section rise from the opposite ends of the arcuate foot 46 as illustrated in Figure 10 and a top cross member 50 joins the upper ends of the side members 49. Joined to the cross member 50 is the bifurcated triangular member 51 in the apex of which turns the pivot 25, with the furcations of the member 51 on opposite sides of the plate 24. A generally similar bifurcated member 52 is placed intermediate the upper ends of and connecting the side members 49 and the furcations of this member 52 are arranged on opposite sides of the plate 22 and the pivot 23 traverses the apex of the furcations and also the apex of the plate 24 with the pivots 23 and 25 vertically aligned as already pointed out and as clearly shown in Figure 4. The support which is generally designated 47 is thereby supported in a backwardly tilted position relative to the framework of the chassis and with the rollers 44 of its foot rolling on the top of the arcuate surface 43 at the front end of the chassis portion 9, in such a way that the support 47 may be readily swung toward either side according to the position of the booms desired with respect to the work.

On the front of the foot 46 is a short arcuate member 54 which is provided with a cable accommodating groove 55 in which is received and fastened the cable 56 which is utilized in a man-

ner to be described for swinging the support 47 from side to side as desired.

Pivotedly supported on the support 47 are the main boom 57 and the digging boom 58.

The main boom 57 is shaped substantially similarly to the main boom of the machine shown in the above mentioned co-pending application and the rear end of the main boom is pivotally supported on the shaft 60 which traverses an intermediate point of the side members 49 of the support 47.

On the top part of the outer end of the main boom are mounted the main sheaves 61 and 62 and inwardly of these is mounted on the top 63 of the boom the shaft 64 on which the small sheave 65 is mounted. As shown in Figure 3 the main boom is tapering in formation.

The digging boom 58 has a front digging section 66 which is similar in outline but much deeper and heavier than the corresponding section of the digging boom of the said co-pending application, and the dumping section 67 of the digging boom is much deeper and has a greater capacity than the corresponding section of the digging boom of the said co-pending application. These improvements in the digging boom are effective in producing more efficient operation of the apparatus as a whole and by increasing the capacity thereof, and much enhance the general efficiency and utility of apparatus of this general character.

The dumping section 67 has the flat bottom 68 from the inner end of which depend the ears 69 which are journaled on the shaft 70 which traverses the lower ends of the side members 49 of the support 47. Relatively low side walls 71 extend only a short distance from the rear end of the dumping section 67 where they terminate in high side walls 72 which have their front ends joining the rounded front wall 73 which has extending forwardly therefrom the ears 74 which are journaled on the shaft 75.

The shaft 75 has journaled thereon the large ears 76 which project from the bottom 77 of the digging section 66. Also journaled on the shaft 75 laterally outwardly of the large ears 76 is the forward end of the racks 78 which work slidably through sleeves 79 which are mounted at the top and opposite sides of the main boom 57 in a manner to be described.

The digging section 66 has rising from the bottom 77 at its rear end the relatively low side walls 80 which are short and terminate in the relatively high walls 81 which terminate at their front ends in the upwardly and outwardly curved front wall 82 which is provided in its upper edge with the sharpened teeth 83 which bite into the earth when the digging section 66 is moved forwardly and downwardly from the position shown in Figure 4 to engagement with the earth.

Near the front end of the flat bottom 77 of the digging section 66 are brackets 84 which journal a shaft 85 on the opposite ends of which are swingably mounted the levers 86 which are engaged therewith at their lower ends and which swing freely along the sides of the digging section and are pivoted as indicated by the numeral 87 at their upper ends to a yoke 88 which extends between the levers 87 at the center of which is fastened the eye 89 to which the sheave 90 is swingably attached. Stop brackets 91 on opposite sides of the high walls 81 of the digging section are arranged at the rear ends thereof to operate as stops to be engaged by the levers 86 in the position illustrated in Figure 4 when the

sheave 90 is pulled upwardly, whereby to lift and swing the section 66 on the axis of the shaft 55 to the position illustrated in Figure 2 of the drawings. The purpose of having the levers 86 and the stops 91 is to permit the digging section 66 to utilize gravity in assuming the different positions thereof, which freedom would not be afforded this digging section were the sheave 90 attached rigidly thereto. This arrangement permits greater amplitude of movement of the digging section than is possible to the digging section of my co-pending application. Resulting from this arrangement is an added crowding effect in the digging, a more sharply angulated 15 tilting during the gravitational passing of the earth from the digging section into the dumping section 67, as well as other advantages which appear herein.

When the digging section 66 is operated from the position shown in Figure 4 to a still further depressed and forwardly moved position in which it engages and digs the earth and becomes filled with earth, the sheave 90 is elevated so as to swing the digging section on the axis of the shaft 75 to the position shown in Figure 2. This position causes the earth in the digging section to fall into the dumping section 67. The racks 78 are then operated to raise the front end of the dumping section 67 to the position shown in Figure 4 wherein the earth slides gravitationally along the flat bottom 68 thereof and empties into the hopper 37 and onto the conveyor belt 32 to be conveyed to the rear end of the conveyor belt frame for deposit on the ground or in a receiving car on the rails 14 or upon a truck of some other kind.

The initial positioning of the main boom 57 is achieved by operating the main boom elevating cable 95. This cable is trained over a pulley 96 on a shaft 97 journaled between the upper parts of the side members 17 of the chassis frame and then brought up around the small sheave 98 which is mounted on the shaft 64 and then brought rearwardly over the sheave 99 which is attached to the cross member 50 and then across and around the small sheave 100 which is mounted on the shaft 64 and then rearwardly and around the sheave 101 which is fastened to the cross member 50 and then fastened as indicated by the numeral 102 to the small sheave 100 as clearly shown in Figure 3. The rear end of the cable 95 is trained over the drum 103 which is mounted on the left hand part of the shaft 104 which is mounted between the side members 17 and the chassis frame.

The cable 105 which operates the sheave 90 is run off the right hand drum 106 which is on the shaft 104 and is trained upwardly over the pulley 26 as clearly shown in Figure 4 and then over the pulley 65 and then over the right hand sheave 62 around the sheave 90 and then upwardly around the sheave 61 and then fastened as indicated by the numeral 106 to the sheave 90. Selective operation of the drums 103 and 106 is arranged for by clutch means and lever operators 107 and 108, respectively, and brake means 109 consisting of bands fastened as indicated by the numeral 110 and laid over brake bands on the ends of the drums and controlled by corresponding brake levers 111 and 112 which are arranged over the platform 113 which is arranged at the right hand side of the right hand standard 17; whereby the drums may be selectively operatively engaged with the shaft 104

which is constantly turned by virtue of its sprocket connection 114, to change the position of the main boom and/or operate the digging section 66 at the will of the operator who stands on the platform 113.

One end of the shaft 104 has fixed thereto the large beveled gear 116 with which is meshed a beveled gear 117 which is fixed on the drive shaft 118 which leads from the engine 119 which is mounted on the rear end of the elevated portion 1 of the chassis, whereby the shaft 104 is constantly driven while the engine is in operation. A cage 120 mounts the front end of the shaft 118 and also a slidably mounted beveled gear 121 which has a universal connection 122 to the rear end of an extensible shaft 123 which has a front end universal connection 124 to a small beveled gear 125 which is, in turn, in mesh with another small beveled gear 126 which is fastened to the shaft 121 which has thereon pinions 128 which respectively drive the individual racks 78. A clutch control 129 operated by the lever 130 which extends through the platform 113 is arranged to operate the beveled gears into and out of engagement for producing reverse rotation of the shaft 123 for raising and lowering the racks 78 as may be required, independently of the rotation of the shaft 104 which continuously rotates in one direction.

The mentioned sprocket connection 114 operates the axle 131 on which the wheels of the trucks 11 and 12 are rigidly fastened through a clutch shaft 132 which is controlled by means of a lever 133 which is exposed for operation just to the rear of the platform 113; through the agency of the gear ring 134 which is operated by a lever 133 to bring about the operative connection between the idler shaft 135 and the axle 131 through the medium of the sprocket connection 136.

The clutch 132 which is directly driven by the sprocket 114 has gear and clutch means generally designated 137 operable by the lever 138 which extends from the platform 113 whereby the vertically arranged drum 139 may be operated in either direction to move the cable 55 which is wound thereon to swing the support 47 from side to side as may be required. The object of the operative connection between the shaft 132 and the axle 131 is to apply the power of the shaft 50, originating in the engine 119, to the axle 131 to move the device forwardly or rearwardly as may be required by the work.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. Tunnel mucking apparatus comprising a chassis including framework, vertical pivot means on said framework, a boom support pivoted by said pivot means, a semi-circular track on the front of said chassis below said support, a forwardly extending foot on said support having rollers running on said track and supporting the front of said support, a main boom pivoted on said support, and a digging boom on said support.

2. Tunnel mucking apparatus comprising a chassis including framework, vertical pivot means on said framework, a boom support pivoted by

said pivot means, a semi-circular track on the front of said chassis below said support, a forwardly extending foot on said support having rollers running on said track and supporting the front of said support, a main boom pivoted on said support, a digging boom on said support, and operating means engaged with said foot for swinging said support from side to side.

3. Tunnel mucking apparatus comprising a chassis including framework, vertical pivot means on said framework, a boom support pivoted by said pivot means, a semi-circular track on the front of said chassis below said support, a forwardly extending foot on said support having rollers running on said track and supporting the front of said support, a main boom pivoted on the front of said support, and a digging boom on said support below said main boom, said digging boom comprising pivotally connected sections, one of said sections being pivoted directly to said support.

4. Tunnel mucking apparatus comprising a chassis including framework, vertical pivot means on said framework, a boom support pivoted by said pivot means, a semi-circular track on the front of said chassis below and forwardly of said support, a forwardly extending foot on the front of said support having rollers running on said track and supporting the front of said support, a main boom pivoted on an upper part of said support, a digging boom on said support below the pivotal point of said main boom, and a conveyor on said chassis leading from a hopper located adjacent the lower end of said boom support, said conveyor being inclined upwardly and rearwardly and being connected to said framework.

5. Tunnel mucking apparatus comprising a chassis including framework, vertical pivot means on said framework, a boom support pivoted by said pivot means, a semi-circular track on the front of said chassis below said support, a forwardly extending foot on said support having rollers running on said track and supporting the front of said support, a main boom pivoted on said support, a digging boom on said support, an operator's platform on said chassis adjacent said

boom support, and control means adjacent said platform for controlling the operation of the booms and said boom support.

6. Tunnel mucking apparatus comprising a chassis including framework, vertical pivot means on said framework, a boom support pivoted by said pivot means, a circular track on said chassis below said support, a foot on said support having rollers running on said track and supporting said support, a main boom pivoted on said support, a digging boom on said support, said digging boom having pivotally connected sections, one of said sections being pivoted to said support, racks pivoted to one of the sections and engaged with said main boom, pinion means on said main boom for operating said racks, and an engine on said chassis operatively connectible to said pinion means.

7. Tunnel mucking apparatus comprising a chassis including framework, vertical pivot means on said framework, a boom support pivoted by said pivot means, a semi-circular track on the front of said chassis below said boom support, a forwardly extending foot on said support having rollers running on the front of said track and supporting said support, a main boom pivoted on an upper part of said support, a digging boom on said support below the pivotal point of said main boom, and means on said framework for raising and lowering said main boom independently of said digging boom.

8. Tunnel mucking apparatus comprising a chassis including framework, vertical pivot means on said framework, a boom support pivoted by said pivot means, a semi-circular track on said chassis below the front of said support, a forwardly extending foot on said support having rollers running on said track and supporting the front of said support, a main boom pivoted on an upper part of said support, a digging boom on said support below the pivotal point of said main boom, and means for operating said digging boom independently of said boom, the last mentioned means having a part supportably engaged with said main boom.

CECIL M. BROWNER.
